UNITED STATES PATENT OFFICE.

WILLIAM MORGANS, OF CHELSEA, ENGLAND.

STEAM-GENERATOR.

SPECIFICATION forming part of Letters Patent No. 691,286, dated January 14, 1902.

Application filed June 21, 1901. Serial No. 65,481. (No model.)

To all whom it may concern:

Be it known that I, WILLIAM MORGANS, a subject of the King of Great Britain and Ireland, residing at Chelsea, in the county of London, England, have invented Improvements in Steam-Generators, of which the following is a specification.

This invention has reference to a construction of steam-generators, according to which one compartment is arranged to surround another, wherein a higher pressure is maintained and the lower pressure in the surrounding compartment is utilized to counteract partly the higher pressure in the surrounded compartment in such a manner as to enable steam at high pressure to be safely generated in the inner or inmost compartment with lighter shells than in steam-generators of cylindrical types as heretofore usually constructed, thereby saving weight, facilitating manufacture, and securing other advantages, as hereinafter described. The number of compartments in such a steam-generator, their relative arrangement, and other details are susceptible of considerable variation. According to one construction two or more cylindrical boiler-shells of different diameters arranged one within another are all connected at their ends to end plates in the manner usually adopted in the construction of cylindrical boilers. The inner or inmost compartment and the annular compartment or compartments between the shells are provided with furnaces or tubes, or both, for the combustion of fuel and the passage of hot gases for the evaporation into steam of the water which is fed into each of the said compartments. The steam thus generated within the several compartments is accumulated in each at the desired respective pressure in the space above the surface of the water in such compartment. The highest-pressure steam required is generated and accumulated in the inner (if there be only two) or inmost compartment. Steam is generated and accumulated in the next outer compartment at a lower pressure, which acts externally upon the shell of the compartment that it surrounds, and thereby reduces the bursting stress upon it, while in like manner if there be a third compartment the bursting stress upon the outer shell of the second compartment is reduced by the pres-

sure of steam generated and accumulated within the third compartment, and so on. By thus utilizing the fluid-pressure within one compartment to relieve strain on the shell of the next inner compartment it is practicable without using shell-plates of great thickness to produce steam of very high pressure, while at the same time obviating drawbacks connected with the generation of steam in long tubes of comparatively small diameter, as in water-tube boilers, and retaining important advantages of well-known cylindrical types of boilers, such as those of the Cornish, the Lancashire, and the Scotch, or ordinary marine classes.

Each compartment may be fed with water quite independently of the other or others; but usually it will probably be found preferable to feed the inner compartment or compartments with hot water drawn from an outer compartment or compartments. This choice of a source of feed-water at different temperatures will tend to facilitate the maintenance of steam at a desired pressure in any given compartment; also, if the inner or higher-pressure compartment or compartments be fed from the outer compartment or compartments less sediment or other objectionable matter will be likely to be carried into the former than would be the case if it or they were fed direct from the hot-well or other source, because the arrangement enables lime, salt, or other deposit or grease or other objectionable matter to be arrested in and blown out from (and gases held in suspension to be liberated from the water in) the outer compartment, so that the water therein is more or less purified or improved as feed-water for the inner compartment, which supplies steam at the highest pressure and from which it is most desirable to exclude sediment, deposit, gases in suspension, or grease, such as may cause injury to the boiler or priming.

As a means of maintaining the pressure of the steam in any given compartment within the desired limits there is or may be provided a system of safety and relief or reducing valves such that while any excess of pressure in the outer or outermost compartment will be relieved by discharging the steam into the atmosphere any excess of pressure in an inner

compartment will be relieved by discharging the steam into the next outer compartment instead of discharging it into the atmosphere; also, a system of relief or reducing valves is 5 or may be provided such that if the pressure in an inner compartment fall below the pressure in the next outer compartment steam or water shall pass from the outer to the inner compartment in order to avoid exposing the 10 intervening shell to any collapsing stress.

The respective compartments are or may be provided with the usual steam and water gages, blow-off cocks, check feed-valves, scum-cocks, safety and other valves, man and mud 15 holes, antipriming pipes, and other mountings and fittings as may be required, and when desired steam and mud drums can also be provided. Heat passing through the shell from the inner compartment will be communicated 20 to the water and steam in the next outer compartment and in that way will be utilized. Only from the outmost shell may heat thus passing be lost, and as the water and steam contained by that shell will be of much lower 25 temperature than that of the steam of the maximum or working pressure required any such loss of heat will be minimized.

The combined boilers may be fired internally or externally, or both. The hot gases 30 may be made to pass or return, or both, through tubes through one or more compartments, and regulators or dampers may be used for controlling the amount of heat communicated to any compartment or part thereof. To facilitate the maintenance of the 35 desired pressure in the respective compartments, the tubes of the several compartments may be of larger or smaller diameter, so as thereby to adjust the heating-surface, and in 40 some cases retarders may be fitted in the tubes for regulating the passage of the hot gases therethrough.

Instead of having its furnace or furnaces located within one of its surrounding or 45 rounded compartments a compound steam-generator, such as described, may in some cases comprise one or more internally or externally fired cylindrical vessels or drums having its or their water space or spaces connected by suitable pipes or passages with the 50 inmost or an inner compartment of a series of compartments, such as hereinbefore described.

In some cases it will be convenient to 55 range the several compartments eccentrically to one another to afford additional or better accommodation for internal furnaces and flues. In such an arrangement the axes of the flues may be substantially in a common 60 horizontal plane or otherwise.

The furnace or furnaces of one or of each compartment may be arranged below or above that or those of the compartment that it immediately surrounds. There may be transverse 65 pockets, channels, or tubes connecting the respective sides of an outer compartment below the top of the compartment it immedi-

ately surrounds, so as to promote circulation of the water. In some cases provision may be made for maintaining the water within 70 the outer compartment or each of said compartments at a level such as to drown the shell of the compartment that it immediately surrounds.

A pair of compound steam-generators such 75 as described can be arranged with an external furnace or furnaces located centrally in relation to the pair in a manner to improve circulation and to obviate or mitigate deposit of incrustation directly over the furnace. In 80 like manner one compound steam-generator may be arranged with an external furnace placed more or less on one side of the vertical plane containing the axis of the generator with similar objects, or the furnace or 85 furnaces of such a steam-generator may be placed internally more or less on one side of the said plane of the generator for improving circulation. Improved circulation may be 90 promoted by providing more tubular heating-surface for one side of a compartment than the other side or by causing more heat to be distributed on one side than the other side.

This general arrangement for raising high-pressure steam in stages in compartments 95 formed by shells of different diameters placed the smaller within the larger and so disposed that steam at the lowest stage of pressure is produced in the outermost compartment and steam at the highest stage of pressure is generated in the innermost compartment lends itself favorably to the application of external firing with grates of any desirable widths, (the sizes of such grates not being controlled by the sizes of the furnace-flues or fire-boxes,) 100 and provided, if need be, with brick arches or linings for promoting complete combustion, because the fire can be applied to the shell of the outer compartment in which the steam being at the lowest stage of pressure permits the use of comparatively thin shell-plates between the fire and the water, which is an advantage for the safe and effective transmission of heat from the furnace to the water to be evaporated.

Instead of generating steam in the outer compartment or compartments, or some of them, it or they or some of them may be utilized simply for counteracting part of the steam-pressure that obtains within the surrounded 110 compartment or compartments, and for this purpose may be charged with some other medium or media, such as air or gas under pressure, and the requisite pressure or pressures may be produced and maintained by a pump 115 or pumps or otherwise. A compartment or compartments so charged may be partially filled with some inelastic medium, such as oil or water. In such a case a relief-valve arrangement is or may be provided that would 120 allow steam from the steam-generating compartment or compartments to enter the air or gas compartment or compartments should the pressure in the latter fall too low and that

likewise would allow the air or gas to enter the next inner compartment should the pressure in the latter fall too low.

Reference being had to the accompanying 5 illustrative drawings, Figure 1 shows in diagrammatic front end view an internally-fired steam-generator of the marine type embodying my invention. Fig. 2 is a longitudinal sectional view corresponding partly to the line 10 A A of Fig. 1 and partly to the line B B thereof. Fig. 3 is a half cross-sectional view corresponding to the line C C of Fig. 2. Fig. 4 is a view similar to Fig. 2 of another construction of steam-generator of a modified marine 15 type. Fig. 5 is a cross-sectional view corresponding to the line D D of Fig. 4. Fig. 6 is a view similar to Fig. 4 of a double-ended steam-generator of a modified marine type. Fig. 7 is a cross-sectional view corresponding 20 to the line E E of Fig. 6. Fig. 8 shows in central cross - section an externally - fired steam - generator with internal flue - tubes. Fig. 9 is a cross-sectional view corresponding 25 to the line F F of Fig. 8. Fig. 10 shows chiefly in cross-section a pair of steam-generators with an external furnace and a common steam-drum. Fig. 11 shows in detail a modification. Fig. 12 shows a cross-section of a 30 compound steam - generator wherein internally-fired small cylindrical vessels or drums are connected by pipes with the inmost compartment of a series arranged according to this invention, these compartments having flue-tubes running through them. Fig. 13 shows an internally-fired steam - generator 35 with the shells arranged eccentrically. Fig. 14 shows an internally-fired steam-generator with eccentrically-arranged shells, furnaces at different levels, and flue-tubes. Figs. 15 40 to 20, inclusive, are detail views illustrating methods of building up the shells of compound steam-generators constructed according to this invention.

In the example shown in Figs. 1, 2, and 3, 45 *a* and *b* indicate two shells riveted to end plates *c*. These shells form two steam-generating compartments *d* and *e*. *f* and *g* are two internal furnaces extending through the inner steam-generating compartment *d* to a 50 combustion-chamber *h*. *k k* are flue-tubes extending through the inner compartment *d* from the combustion-chamber *h* to a chamber *m*, arranged at the front of the generator. *n n* are flue-tubes extending through the outer 55 compartment *e* from the front chamber *m* to a rearwardly-arranged uptake *o*. The products of combustion pass from fires in the furnaces *f* and *g* into the combustion-chamber *h*, through the flue-tubes *k* into the chamber *m*, and thence through the flue-tubes *n* into the uptake *o*. *p* is a feed-pump or injector 60 arranged to draw water from any suitable vessel *q*. *r* is the delivery-pipe. *s* and *t* are branch pipes, one to each compartment of the generator. *u* and *v* are valves in the 65 respective branch pipes. *w* is the steam-supply pipe to the pump *p*, and *y* is a cock in

the said steam-supply pipe. This arrangement enables water to be fed at will to either compartment of the generator. *z* is another 70 feed-pump. Its suction-pipe *1* has branches *2* and *3*, one to each compartment of the generator. *4* and *5* are valves in the said branches. *6* is the delivery-pipe with branches *8* and *9*, one to each compartment of the generator. *75* *10* and *11* are valves in the branches *8* and *9*. *12* is the steam-supply pipe to the pump *z*, and *13* is a cock therein. This arrangement 80 enables hot water to be transferred at will from one compartment to another. *14* *14* *80* are connections each containing a relief or reducing valve *15* between the inner compartment *d* and the outer compartment *e*. The connections *14* extend from the steam-space of the compartment *d* to the lower portion of the compartment *e*. Each pipe *14* is 85 also provided with a branch *16*, leading to the steam-space of the compartment *e* and provided with a stop-valve *17*. *18* *18* are loaded safety-valves connected to the compartment *90* *d* and adapted to act should the relief-valves *15* through any cause cease to act. *21* is a safety-valve loaded to the lower pressure it is desired to maintain in the outer compartment *e*. With this arrangement when the pressure 95 in the inner compartment *d* rises above that for which the valves *15* are set such excess will be relieved by the opening of the valves *15*, past which steam will flow into the outer compartment *e*, entering the water near the 100 bottom or, if preferred, entering the steam-space near the top through the valve *17*. *19* *19* are further connections between the compartment *d* and the compartment *e*, provided with relief-valves *20* *20*, adapted to allow 105 steam from the outer compartment to enter the inner compartment, should the pressure in the latter be at any time less than the pressure in the former. Any excess of pressure in the outer compartment *e* will be relieved by the opening of the safety-valve *21*, 110 through which steam will escape into the atmosphere. *22* *22* are water-gages for each compartment. *23* is a steam stop-valve which may or may not be connected with an internal antipriming-pipe for delivering steam 115 from the inner compartment for driving the engines or other purposes. It will be understood that each compartment must be provided with suitable pressure-gages, manholes, 120 mud-holes, blow-off cocks, and other usual and necessary mountings and fittings. There may be only two compartments, as shown, or there may be more than two. In the latter case each intermediate compartment has feeding and relief devices and connections with the inner and outer adjacent compartments, 125 such as hereinbefore described with reference to the two compartments of the example shown in Figs. 1, 2, and 3.

In the example shown in Figs. 4 and 5, *d*, *e*, and *e'* are three steam-generating compartments, *f* and *g* are internal furnaces, and *k k* are flue-tubes extending through the com- 130

partments from a combustion-chamber *h* to a chamber *m*, from whence they pass by flue-tubes *n* to the uptake *o*. 24 is a rear water and steam chamber connected to the outmost 5 compartment *e'* by means of short tubes 25.

In the example shown in Figs. 6 and 7 there are two steam-generators, similar to that shown in Figs. 4 and 5, but arranged back to back, the uptake leading from a chamber 26, arranged 10 between the two generators, and around the combustion-chamber *h* and the hot gases passing from the furnace-flues to the combustion-chamber *h* through the tubes *k* to the front chamber *m* and back by the tubes *n* to the chamber 26. 15

Figs. 8 and 9 show a steam-generator comprising two steam-generating compartments *d* and *e*, an external furnace 27, and flue-tubes *k*, extending through the compartment 20 *d*.

Fig. 10 shows two steam-generators connected by pipes 29 to a common steam-drum 30 and heated by an external furnace 28, centrally arranged, so as to promote in the steam-generators circulation in the directions of the arrows, and to assist such circulation the two generators are provided with transverse tubes 31, connecting opposite sides of the compartment *e* below the top of the inmost compartment *d*, and like tubes 32, connecting opposite sides of the compartment *e'* below the top of the compartment *e*. In lieu of the tubes 31 and 32 the shells of the compartments *d* and *e* may be provided at intervals 30 along their upper parts with transverse pockets 33, as shown in Fig. 11. 35

In the generator shown in Fig. 12 there are three cylindrical vessels 34, with three internal furnaces 35. These three vessels are connected 40 to the inmost compartment *d* by pipes 36. Cross-tubes 31 32 for connecting the water-spaces of the respective inner compartments may be provided, as shown by dotted lines. 45

Fig. 13 shows three steam-generating compartments *d e e'*, arranged eccentrically. The inmost contains two internal furnaces *f g*, and each of the other compartments contains one internal furnace 37. *k* and *n* are flue-tubes. 50

Fig. 14 shows two steam-generating compartments *d* and *e*, eccentrically arranged, in each of which there is a pair of internal furnaces *f g* or *f' g'*. *k* represents flue-tubes. 55

The shell of a steam-generator constructed with compartments one within another, as set forth, may be built up in any convenient manner, according to modern boiler-shop practice. Figs. 15 to 19, inclusive, illustrate 60 several methods of construction in which an outer compartment is provided with an end plate *c* separate from the end plate of an inner compartment and in which the plates are flanged for dispensing with the use of angle-irons. 65

Fig. 20 shows a construction of steam-gen-

erator according to this invention in which the end plate *c* is common to the several compartments, but is of different thicknesses for each compartment, according to the pressures 70 it is proposed to maintain.

The surrounding compartment or compartments might in some cases be subdivided by longitudinal or other partitions instead of being uninterrupted annuli; but I prefer the latter for avoiding undue strains as far as practicable in the construction and working of the boiler. 75

What I claim is—

1. A steam-generator, comprising two or 80 more steam-generating compartments one surrounding another and connected together in such a way that the pressure of the steam therein decreases from the inmost compartment to the outmost compartment. 85

2. A steam-generator comprising two or more steam-generating compartments one surrounding another, and means for feeding hot water to the inner from the outer of said compartments. 90

3. A steam-generator comprising a series of steam-generating compartments one surrounding another with the interiors of the compartments normally disconnected the one from the other and means whereby any excess 95 of pressure in a surrounded compartment will be relieved by discharging steam or water therefrom into an outer compartment.

4. A steam-generator comprising two or more steam-generating compartments, one 100 surrounding another, means for feeding hot water to the inner from the outer of said compartments, and means whereby any excess of pressure in a surrounded compartment will be relieved by discharging steam or water 105 therefrom into an outer compartment, substantially as described for the purpose specified.

5. A steam-generator comprising more than two cylindrical boiler-shells of different diameters arranged one within another and forming an intermediate compartment or intermediate compartments, end plates to which said shells are connected, and means for feeding hot water from an inner compartment to an 110 outer compartment, substantially as described for the purpose specified. 115

6. A steam-generator comprising more than two cylindrical boiler-shells of different diameters arranged one within another and forming an intermediate compartment or intermediate compartments, end plates to which said shells are connected, means for feeding hot water from an outer to an inner compartment, and means whereby any excess of pressure in 125 a surrounded compartment will be relieved by discharging fluid therefrom into an outer compartment, substantially as described for the purpose specified.

7. A steam-generator comprising steam-generating compartments one within another with the interiors of the compartments nor-

mally disconnected the one from the other, and means for supplying fluid from one compartment to another compartment.

8. A steam-generator comprising fluid-tight compartments one within another, and means for supplying fluid to each of the said compartments independently of the other compartments or compartments.

9. A steam-generator comprising fluid-tight compartments one within another, an inner one of the said compartments containing water and steam, and an outer one of the said compartments containing fluid at a pressure less than the said steam.

10. A steam-generator comprising fluid-tight compartments one within another, an inner one of the said compartments containing water and steam, and an outer one of the said compartments containing air at a pressure less than the said steam.

11. A steam-generator comprising compartments one surrounding another, means for supplying water to an inner one of the said compartments, means for supplying fluid to an outer one of the said compartments, and means for enabling fluid to pass automatically from an outer one to an inner one of the said compartments should the pressure in the said outer compartment exceed the pressure in the said inner compartment.

12. A steam-generator comprising compartments one surrounding another, means for supplying water to an inner one of the said compartments, means for supplying fluid to an outer one of the said compartments, means for enabling excess of pressure in the said inner compartment to be relieved automatically by the escape of fluid therefrom into the said outer compartment, means for enabling excess of pressure in the said outer compartment to be relieved automatically by the escape of steam or fluid therefrom into the said inner compartments, means for preventing the pressure in the said inner com-

partment from exceeding a definite amount 45 and means for preventing the pressure in the said outer compartment from exceeding a definite amount.

13. A steam-generator comprising compartments one surrounding another, means for supplying water to each of the said compartments, means provided for each of the said compartments to enable excess of pressure therein to be relieved automatically by the escape of fluid therefrom into the other of the 55 said compartments and means provided for each of the said compartments to prevent the pressure therein from exceeding a definite amount.

14. A steam-generator comprising compartments one surrounding another, means for supplying water to each of the said compartments independently of the other, means for supplying hot water from an outer one of the said compartments to an inner one of the 65 said compartments, means provided for each of the said compartments to enable excess of pressure therein to be relieved automatically by the escape of fluid therefrom into the other of the said compartments, and means provided for each of the said compartments to prevent the pressures therein from exceeding definite relations to each other.

15. A steam-generator comprising compartments one surrounding another, an outer one 75 of the said compartments containing steam at a lower pressure than the inner of the said compartments, and a chamber or water-back connected to the said outer compartment and forming, with the said inner compartment a 80 combustion-chamber.

Signed at 77 Cornhill, London, E. C., England, this 7th day of June, 1901.

WILLIAM MORGANS.
